UNITED STATES PATENT OFFICE.

GEORGE C. HICKS, JR., AND RALPH C. ENYART, OF CONNERSVILLE, INDIANA, ASSIGNEES TO THE P. H. & F. M. ROOTS COMPANY, OF CONNERSVILLE, INDIANA.

ROTARY BLOWER.

1,098,440.

Specification of Letters Patent.

Patented June 2, 1914.

Application filed June 9, 1913. Serial No. 772,561.

To all whom it may concern:

Be it known that we, GEORGE C. HICKS, Jr., and RALPH C. ENYART, citizens of the United States, and residents of Connerville, Fayette county, Indiana, have invented certain new and useful Improvements in Rotary Blowers, of which the following is a specification.

In rotary blowers working under comparatively high pressure, the heat due to compression has been found in some cases to lead to undesirable results. To overcome this, provision has heretofore been made for circulating cooling water through the lobes of the impellers, but the construction, while accomplishing the desired results, has not been altogether satisfactory.

Our present invention relates to improved means for effecting the circulation of cooling water through the impellers and the improvements will be readily understood from the following description taken in connection with the accompanying drawings in which:

Figure 1 is a diametrical section, in the plane of line *a* of Figs. 2 and 3, of an impeller fitted with our improved water-circulating means: Fig. 2 an end elevation of the same: Fig. 3 a vertical transverse section of a portion of the impeller, in the plane of line *b* of Fig. 1: and Fig. 4 a vertical section of the water inlet connection in the plane of line *a* of Figs. 2 and 3.

In the drawings:—1, indicates an impeller of a rotary blower, illustrated as of the well known Roots type, the impeller being a hollow casting; 2, the chamber in one of the lobes of the impeller; 3, the chamber in the other lobe of the impeller; 4, the shaft on which the impeller is firmly secured in the usual manner; 5, partitions arranged transversely in the chambers of the lobes to give strength to the impeller, these partitions having openings through them so that, while each partition divides the chamber of a lobe into two compartments, the two compartments are in free communication with each other; 6, the recess usually provided in the hubs of impellers to avoid the necessity for making a fit between the hub and the shaft except at each end of the impeller; 7, apertures leading from this recess to the chambers of the impellers, preferably at those compartments of the chambers which are farthest from the end of the impeller at

which the cooling water is to be admitted: 8, an axial bore extending inwardly from one end of the impeller shaft; 9, a boss secured to the outer end of the shaft and having a circular exterior concentric with the shaft and provided with an axial bore: 10, a pipe having its inner end tightly fitted, as by screwing, to the inner end of the bore 8 of the shaft and having its outer end similarly secured to boss 9, the axial bore of the boss forming an outward continuation of the bore of the pipe; 11, a passageway extending radially from the inner end of the axial bore of the pipe through the shaft and through the hub of the impeller and into a chamber in one of the lobes of the impeller; 12, a water-supply pipe to deliver water through the bore of boss 9 and pipe 10; 13, a swivel connection, provided with a stuffing-box, connecting pipe 12 with boss 9 so that while the impeller and the shaft and the boss rotate pipe 12 may remain stationary; 14, that portion of the axial bore 8 of the shaft surrounding pipe 10, it being understood that bore 8 is larger than the exterior of pipe 10 so as to leave a water passage around the outside of the pipe; 15, a radial passage leading from the inner portion of bore 8 to the chamber of the lobe of the impeller opposite the lobe into which passage 11 leads; 16, longitudinal passages formed in boss 9, their inner ends communicating with bore 8 of the shaft and their outer ends terminating at about the mid-length of boss 9; 17, radial passages extending from the outer ends of passages 16 and preferably through a collar formed on the boss; 18, a stationary casing surrounding the boss and the collar, this casing being diametrically divided so as to permit of its being put upon the boss, it being understood that this casing need not fit or touch the boss at any point; 19, a water-discharge pipe leading down from the casing; 20, lugs provided upon the wall of the casing to serve, if desired, in securing the casing against a fixed support, the casing of the blower for instance; and 21, annular projections inwardly from the side walls of casing 18, concentric with the axis of the impeller, these projections freely straddling the collar of the boss containing the passages 17.

The cooling water entering inlet-pipe 12, preferably being pumped thereto, passes through the swivel connection and the axial

bore of the boss and through pipe 10 and then through passage 11 into one of the compartments of lobe 2 of the impeller. From there the water goes into the other compartment of lobe 2, and thence through apertures 5 7 and recess 6 to a compartment of lobe 3, and thence to the other compartment of that lobe, and thence through passage 15 to the outer portion 14 of the axial bore of the shaft, and thence through passages 16 and 10 17 from which latter passages the water is thrown by centrifugal force into the casing, from which it departs by outlet pipe 19. The circulating water carries away heat 15 from the impeller, and it is manifest that no close fitting of the casing with the boss is required to take care of the discharge water, no water-tight fits being required between casing 18 and the boss, the conditions 20 of construction being such that it is desirable that a very liberal degree of looseness be provided between the boss and the contiguous portions of the casing.

We claim:—

25 1. A rotary blower comprising an impeller having chambered lobes whose chambers communicate with each other, a shaft having the impeller secured upon it and having an axial bore communicating with one of the 30 lobe-chambers through the medium of a transverse passage, a boss concentrically mounted on the outer end of the shaft and having a passage placing the periphery of the boss in communication with the outer 35 portion of said axial bore, a casing loosely surrounding the boss and adapted to receive water discharged from the periphery of the boss, a discharge-pipe connected with the casing to carry away the water received 40 from the boss, a pipe having its inner end secured at the inner end of said axial bore, a transverse passage placing the inner end of said pipe in communication with a lobe-chamber other than the one with which said 45 axial bore is in communication, said boss having an axial passage forming an outward prolongation of said pipe, a stationary inlet pipe, and a swivel connection between said inlet-pipe and the axial bore of the boss, 50 combined substantially as set forth.

55 2. A rotary blower comprising, an impeller having chambered lobes whose chambers communicate with each other, a shaft having the impeller secured upon it and having an axial bore communicating with one of the 60 lobe-chambers through the medium of a transverse passage, a collared boss concentrically mounted on the outer end of the shaft and having a passage placing the periphery of the collar of the boss in communication with the outer portion of said axial bore, a casing loosely surrounding the boss and adapted to receive water discharged 65 from the periphery of the collar of the boss, a discharge-pipe connected with the casing

to carry away the water received from the collar of the boss, a pipe having its inner end secured at the inner end of said axial bore, a transverse passage placing the inner end of said pipe in communication with a lobe-chamber other than the one with which said axial bore is in communication, said boss having an axial passage forming an outward prolongation of said pipe, a stationary inlet pipe, and a swivel connection between said inlet-pipe and the axial bore of the boss, combined substantially as set forth. 70 75

3. A rotary blower comprising, an impeller having chambered lobes whose chambers communicate with each other, a shaft 80 having the impeller secured upon it and having an axial bore communicating with one of the lobe-chambers through the medium of a transverse passage, a collared boss concentrically mounted on the outer end of the 85 shaft and having a passage placing the periphery of the collar of the boss in communication with the outer portion of said axial bore, a casing loosely surrounding the boss and adapted to receive water discharged 90 from the periphery of the collar of the boss, annular projections inwardly from the side-walls of the casing to near the collar of the boss, a discharge-pipe connected with the casing to carry away the water received 95 from the boss, a pipe having its inner end secured at the inner end of said axial bore, a transverse passage placing the inner end of said pipe in communication with a lobe-chamber other than the one with which said axial bore is in communication, said boss having an axial passage forming an outward prolongation of said pipe, a stationary inlet-pipe, and a swivel connection between said inlet-pipe and the axial bore of the boss, 100 combined substantially as set forth. 105

4. A rotary blower comprising, an impeller having chambered lobes whose chambers communicate with each other, a shaft having the impeller secured upon it and having an axial bore communicating with one of the lobe chambers through the medium of a transverse passage and carrying a passage 110 extending outwardly from said axial bore at a point endwise outside the impeller, a casing loosely surrounding the shaft at said last-mentioned passage and adapted to receive water discharged therefrom, a discharge-pipe connected with said casing to carry away the water received thereby, a 115 supply-pipe disposed within the axial bore of the shaft and having its inner end in communication with a lobe-chamber other than the one with which said axial bore is in communication, and a stationary inlet-pipe having swiveled connection with said supply-pipe, combined substantially as set forth. 120 125

5. A rotary blower comprising, an impeller having chambered lobes whose cham- 130

bers communicate with each other, a shaft having the impeller secured upon it and having an axial bore communicating with one of the lobe chambers through the medium of a transverse passage and carrying a collar provided with a passage extending outwardly from said axial bore at a point endwise outside the impeller, a casing loosely surrounding the shaft at said last-mentioned passage and adapted to receive water discharged therefrom, annular projections inwardly from the side walls of the casing to near said collar, a discharge-pipe connected with said casing to carry away the water

received thereby, a supply-pipe disposed within the axial bore of the shaft and having its inner end in communication with a lobe-chamber other than the one with which said axial bore is in communication, and a stationary inlet-pipe having swiveled connection with said supply-pipe, combined substantially as set forth.
